UNITED STATES PATENT OFFICE.

JOHN A. KELLEY AND STEPHEN W. ROUSE, OF FREMONT, MINNESOTA.

GRINDING-MILL.

SPECIFICATION forming part of Letters Patent No. 643,412, dated February 13, 1900.

Application filed June 28, 1899. Serial No. 722,167. (No model.)

To all whom it may concern:

Be it known that we, JOHN A. KELLEY and STEPHEN W. ROUSE, citizens of the United States, residing at Fremont, in the county of Winona and State of Minnesota, have invented certain new and useful Improvements in Grinding-Mills; and we do hereby declare the following to be a full, clear, and exact description of the invention, such as will enable others skilled in the art to which it appertains to make and use the same.

This invention relates to improvements in grinding-mills, and more particularly in the means employed to maintain the millstones in proper relative grinding relation to each other.

The objects of the invention are to provide a simple and durable end thrust-bearing for the shaft of the adjustable millstone capable of exerting the necessary pressure on the shaft without unnecessarily increasing the friction and wear on the shaft or the bearing, to provide large antifrictional surfaces for said thrust-bearing, and to generally improve the construction of the end thrust-bearing for the millstone-shaft.

With such objects in view the invention is embodied in the parts, combinations, and arrangements of parts, as hereinafter described, and more particularly set forth in the claims.

In the accompanying drawings we have shown a practical embodiment of the invention; but we desire it understood that we do not limit the improvements in their useful applications to the particular construction therein illustrated.

In said drawings, Figure 1 is an elevational view illustrating our invention; and Fig. 2 is a sectional view on the line 2 2, Fig. 1.

Referring to the accompanying drawings, wherein like reference characters refer to similar parts throughout both views, A indicates a part of the framework of a grinding-mill and which supports the several parts of our improvements. Slidably and rotatably mounted in bearings b b in bars B B of this frame is the shaft C, which carries the adjustable millstone. (Not shown.) This shaft C is provided with a suitable driving-pulley (indicated at D) and has at its end a disk or head E, provided with a beveled or inclined bearing-surface e.

Mounted to slide in bearings f, supported by the bar B and a frame-bar G parallel therewith, are two rods, (indicated at H H.) Secured to and connecting these rods H H is a frame I, to which and to the frame-bar G is secured a spring J, acting to hold the sliding frame I up or away from the end of the millstone-shaft C. Fulcrumed on a pin k on the supporting-frame is a lever K, having a bearing slot or hole k', in which bears a stud or pin k" on the sliding frame I. Surrounding the stud or pin k" to receive the thrust of the lever is a yielding cushion or spring L. Any suitable means, such as a weight or screw, (not shown,) may be provided for exerting the necessary pressure on the lever K, and through it on the sliding frame I and millstone-shaft C.

M M indicate large circular disks or wheels carried by axles m m and rotatably mounted in bearings N N on the sliding frame I. The axles m m are arranged at an angle relative to each other, and consequently the large disks M M are arranged angularly relative to each other, the relation being such as to cause the peripheries of the disks M M to bear flat against the inclined or beveled bearing-surface e on the head E on the millstone-shaft C, thus forming an extended movable antifrictional thrust-bearing for the head E.

In the drawings the sliding frame and the bearing-disks are shown as being above and bearing down on the shaft; but it is evident that with only obvious changes in the weight or moving means for the lever K the improvements are equally adapted for use on the lower end of a shaft for exerting upward pressure, and the improvements are also applicable to horizontal shafts.

Having thus described our invention, what we claim is—

1. The combination with a supporting-frame, and a slidable millstone-shaft journaled in bearings on the same, of a sliding frame, a spring acting to move said sliding frame in one direction, a lever fulcrumed to said supporting-frame and having a cushioned engagement with said sliding frame, means for moving said lever to move said sliding frame against the tension of said spring, and rotatable disks journaled on said sliding frame at an incline to each other and

bearing against a part carried by said mill-stone-shaft, substantially as described.

2. The combination with a supporting-frame having cross-pieces B, G, and a mill-stone-shaft journaled in bearings on said cross-pieces, of a sliding frame having bars H sliding in bearings on said cross-pieces, a spring for moving said sliding frame in one direction, a lever fulcrumed to said supporting-frame and engaging said sliding frame, means acting on said lever for moving said sliding frame against the action of said

spring, and rotatable disks journaled on said sliding frame and bearing against a part carried by said millstone-shaft, substantially as described.

In testimony whereof we affix our signatures in presence of two witnesses.

JOHN A. KELLEY.

STEPHEN W. ROUSE.
